UNITED STATES PATENT OFFICE.

FRANK HUMPHRIS, OF PARKSTONE, DORSET, ENGLAND.

SHEET METAL.

Application filed February 25, 1927, Serial No. 171,027, and in Great Britain October 28, 1925.

This invention relates to improvements in and connected with the feeding of sheet-metal through presses or like machines and is carried into effect by slitting a blank or untrimmed sheet of metal adjacent two of the marginal edges thereof remote one from the other to form tongues, by means of which slits and tongues such sheet may be moved forwardly and guided accurately and in a straight path for a definite pitch-distance step-by-step as it is impelled by the feeding parts or pawls of any suitably formed feeding-mechanism of the known kind embodied in any press or like machine and by these feeding parts or pawls engaging in the slits it is possible to feed the said sheet with absolute precision any number of times into, through and out of a press or other machine or under the action of any number or sets of punch and die-tools which may be necessary for operating on the said sheet for the purpose of producing accurately formed articles therefrom; but it will be obvious that where multiple operations are essential the feeding of such sheet must be regulated to travel a definite pitch distance and the movement thereof made in a straight path at each feed-stroke and that these conditions must apply at all times whilst the sheet is being fed through a press or like machine; these conditions are of the highest importance as failure to obtain exact location for and during the operations in the production of articles from the said adapted or prepared sheet ensures the resulting product or article being inaccurately formed and in most cases useless.

Where several accurately formed articles are produced either end to end or side by side or in a row at one and the same time, and the production thereof is arranged to occur step-by-step or in successive rows, and in which articles are cut out from a blank sheet of metal so as to leave a perforated sheet of metal or residue of mesh-like form consisting of strands of metal resulting from the blanking out of articles from such sheet-metal in rows; but such strands of mesh-like form remain integral with the two previously, perforated, notched or slit, marginal edges of such sheet; any inaccuracy in the location of the slits and tongues in the said sheet either spoils the articles produced from the sheets or breaks the die-tools.

According to this invention tongue-forming slits are made in sheets of metal adjacent

two marginal edges thereof, one remote from the other, by means of accurately sized and spaced punches arranged in one or more rows to coact with their complementary dies and the said punches of any one row are arranged to be in true alignment one with the other and parallel with the punches of any other row and are mounted in a press or other machine of the known kind so that one or more rows of accurately spaced slits and tongues are produced at one and the same time.

This invention will now be described and illustrated with reference to the accompanying drawing; it is to be understood however that the drawings do not illustrate adapted and prepared sheets of metal of full size, they only illustrate parts of such sheets of metal and the illustrations are given merely by way of example.

In these drawings:

Figure 1 is a face view of two pieces of an adapted and prepared sheet of metal, one piece being cut from one and one piece from the other margin or side edge of one and the same sheet of metal, showing one row of slits and the resulting tongues or spike-like projections formed whilst slitting each piece as they are located near each side edge or margin of the sheet.

Figure 2 is a sectional view, on either one of the lines 5—5 or 5^a—5^a of Figure 1, showing the tongues or spike like projections, and one form of contacting or abutting faces provided in the sheet.

Like letters of reference refer to like parts throughout the drawings.

In the embodiment of the invention illustrated a plain or blank sheet of metal *a* is slit at regular intervals, as at *e*, adjacent one or both of its side edges to form one or more rows of tongues *e*², which tongues preferably have their ends pointed and are bent out of the plane of one face of the sheet to form means for guiding the sheet through a machine which is to act upon it. The ends of the slots form contacting or abutting faces *e*¹, for engagement by that part of the machine, for example a toothed wheel, which serves to impel the sheet through the machine. Where more than one row of contacting faces *e*¹ and tongues *e*² are formed in the sheet the contacting faces *e*¹ adjacent one edge of the sheet are preferably in alignment with those adjacent the opposite edge of the sheet on lines transverse to the rows

of contacting faces and tongues; and where more than one row of contacting faces e' and tongues e^2 are formed in the sheet it is essential that all of the rows shall be parallel, 5 one to the other, as shown by the dotted lines 5—5 and 5^a 5^a in Figure 1. These dotted lines illustrate how a straight line must pass in each case along a true centre line extending lengthwise of the tongues e^2 , and it 10 is essential that said lines be parallel to a dotted centre line X—X which represents the longitudinal centre-line on the sheet of metal a .

It is also essential that the contacting 15 faces e' , be of sufficient width for engagement by a feeding part, finger, pawl, detent, toothed wheel or other suitably formed member of the feeding mechanism of a press or like machine. The contacting faces e' and 20 the tongues e^2 serve in the place of several of the members ordinarily employed in the known forms of sheet feeding mechanisms, since the contacting or abutting surfaces e' form, in effect, the equivalent of a toothed 25 rack, and the tongues e^2 serve as guiding means and, therefore, make it possible to feed a sheet of metal so prepared through a press or like machine any number of times, either in an intermittent or in a continuous 30 manner and without the aid of rollers, guides, or the comparatively complicated spacing and feeding-mechanism ordinarily employed.

The contacting or abutting surfaces e' and 35 tongues e^2 when provided in sheets of metal, serve in addition to the feeding thereof as spacing, guiding and locating means and as such they are employed in conjunction with any known form of impelling and/or retaining 40 fingers, detents, pawls, or other suitably formed members used or embodied in any suitably formed feeding mechanism of a press or like machine.

Either two or more rows of contacting 45 faces e' and tongues e^2 may be employed and arranged, preferably, but not necessarily, in staggered relation to the other row local thereto in any side edge or margin of a sheet of metal a .

According to this invention, a plain or 50 blank sheet of metal a is provided by punches and dies mounted in one press or the like with the means hereinbefore described, so as to enable it after it has been 55 adapted or prepared to coact any desired number of times with impelling mechanism of another press or other machine, and so that finished, or partly finished articles may be accurately formed or cut out from any 60 part other than the slit margins of such sheet metal a by one or more repetition punch-and-die operations performed thereon with an accuracy of feed hitherto not obtained.

In carrying this invention into effect it is 65 not essential that the original sinuous or

rough edges a' , which occur on untrimmed plain or blank sheets of metal a , be cut or sheared off so as to provide edges which are parallel one to the other, as by the use of this invention the sinuous or rough edges a' 70 may remain and retain that sinuous outline normal in untrimmed commercial sheet metal, as illustrated in the drawings, and where any sheet metal is adapted or prepared according to this invention the presence of sinuous edges a' on such sheet metal presents no disadvantage or obstruction to the feeding or guiding of such sheet through a press or other machine because the said sheet is actually guided by the contacting 8 faces e' and tongues e^2 . It accordingly is unnecessary to provide the sheet with straight edges or to provide guides to contact with the sheet at any period during the impelling or feeding of the said sheet through 8 a press or other machine.

When using sheets of metal which have been prepared in two of the margins thereof remote one from the other as just described according to this invention, for example in the manufacture of steel-pens in which it is known that the last and by far the most important operation performed by mechanical means is that of "slitting", for the reason that the edges of the cutters used for this purpose are equal in delicacy to the cutting edges of a razor, therefore any error in the feeding or in the exact location of the adapted or prepared sheet of metal would inevitably not only spoil one row of steel-pens at each "slitting" operative stroke of the machine in which "slitting" tools are mounted, but might cause breakage of the tools. These disadvantages are avoided by the provision of the guiding tongues e^2 . The pointed ends of the said guiding-tongues e^2 must be so accurately positioned or located in the sheet of metal that, if a straight line extends through all the corresponding points in each row thereof, such points and the said line must be parallel to the center line X—X and each said line on each row must be parallel to all the other lines extending through like points or faces on any other row of tongues in the margins of the said sheet of metal.

It will be obvious that a large variety of articles can be made from sheets of metal which have been adapted or prepared according to this invention and most of these require the same accuracy in the location and guiding of the said sheets on to the die-tools by which the said articles have to be produced as is required for the sheets of metal from which the steel pens hereinabove referred to are made.

I claim:

1. A sheet of metal having untrimmed edges and slotted adjacent said edges to form guiding tongues bent out of the plane of one

face of the sheet, the ends of the slots so formed being equally spaced apart in parallel rows and serving as impelling faces, the said faces being in alignment on lines transverse to the rows.

2. A sheet of metal having untrimmed edges and also having a plurality of apertures equally spaced apart and formed by tongues bent out of the plane of one face of the sheet and extending in the direction of

the length of the sheet, said apertures having sheet impelling faces arranged in parallel lines adjacent to the edges of the sheet.

3. A sheet of metal according to claim 2 wherein the ends of the tongues are pointed and the points of the tongues of each row extend in the same direction and are aligned longitudinally of the sheet. 15

FRANK HUMPHRIS.
